UNITED STATES PATENT OFFICE.

MAURICE FRANCIS HUXLEY, OF HENDON, LONDON, ENGLAND.

AEROFOIL.

1,376,337.

Specification of Letters Patent.

Patented Apr. 26, 1921.

Application filed August 8, 1919. Serial No. 316,090.

To all whom it may concern:

Be it known that I, MAURICE FRANCIS HUXLEY, a subject of the King of Great Britain, residing at Hendon, London, England, have invented certain new and useful Improvements in Aerofoils, of which the following is a specification.

This invention relates to improvements in aerofoils used on aeroplanes, and other aircraft, and also to sections of aerofoil shape such as hydrovanes and the like.

In the case of an aeroplane it is usual to have aerofoils of a definite section, that is the shape of each aerofoil cannot be altered, except as regards the rear portion or trailing edge which is provided with hinged flaps or ailerons for the purpose of balancing and in some cases to act as an air brake.

The lifting property and efficiency of an aerofoil depend on the general curvature of the aerofoil, particularly on the angles of entry and trail and the position of the maximum ordinate. While these angles should be small for high speed, they should be large for low speed. The performance of present day aeroplanes is handicapped by the limitations due to a fixed wing section. The speed range and lifting power of a machine can be enhanced if the shape of the aerofoil is capable of variation.

The object of the invention is to render this variation possible, in a simple and effective manner, and preferably so that the construction of the aerofoil will be rendered economical and without undue increase in weight.

With this object in view the invention consists in an aerofoil having an initial section designed to give a high lift/drift ratio and provided with a hinged nose and a hinged rear flap, forming separate rigid elements, the two being inter-connected so that they are both lowered or both raised to vary the angles of entry and trail simultaneously for the purpose of changing the camber of the section so as to increase or decrease the lift co-efficient of the aerofoil, without a corresponding dangerous displacement of the center of pressure likely to render the aerofoil unstable.

Under conditions when a high lift/drift ratio is the important factor the aerofoil is adjusted to the initial section, whereas under other conditions when a high lift co-

efficient is of primary importance the camber of the aerofoil is altered so that the angles of entry and trail are increased.

By interconnecting the forward and rear flaps so that both move up or both move down simultaneously, the danger of excessive stresses being thrown onto the control mechanism under certain conditions, for example at small or negative angles of incidence, may be avoided, as the pressure on the nose may be partly balanced by the pressure on the rear flap.

In large machines, for stabilizing purposes the leading and trailing flaps may be so arranged that they may be operated to increase the camber on one side and decrease it on the other side.

The invention permits of the central portion of the wing between the spars, remaining fixed as is the present practice, so as to maintain the present character of the wing structure. In this way it facilitates manufacture as the component parts of the aerofoil can be made separately and standardized, so that renewals are facilitated. Moreover, it permits of the rear flap being further deflected positively either downward or upward and independently of camber deflection, by a separate control corresponding to what is generally known as aileron control.

A preferable combination is a hinged front portion capable of rotating on the front spar, and a rear portion or flap, extending throughout the rear portion of the wing and hinged to the rear spar. It is also preferred to have the front flap hinged in such a manner that when it is in one position the upper and lower surfaces are both continuous and faired.

In the accompanying drawings:—
Figure 1 is a cross section, and

Fig. 2 is a plan of part of an aerofoil with fabric removed to show the mechanism for controlling the forward and trailing sections.

Fig. 3 is a plan of half of the aerofoil or wing, diagrammatically indicating the cables for the controlling mechanism.

Fig. 4 is a cross section of a modified form of the apparatus shown in Fig. 1.

Fig. 5 is a cross section through two aerofoils of a bi-plane with the invention applied so that trailing sections of the two

planes can be controlled independently of the camber control operating the forward and rear sections.

Fig. 6 is a plan of the upper plane shown 5 in Fig. 5, but on a smaller scale.

Figs. 7 and 8 are cross sections, and Fig. 9 a plan, illustrating further forms of the invention.

The aerofoil shown in Figs. 1 to 3 is constructed in three sections; a central fixed or main section 1, the forward and rearward edges of which are formed by the usual main spars 4 and 5, a forward section or nose 2 forming in itself a rigid structure, hinged 15 at 13 to the forward main spar 4, and a rear flap or trailing portion 3 extending throughout the whole length of the aerofoil and hinged to the rear spar 5 at 24. The nose 2 is provided with a suitable number of levers 20 or arms 6, for instance two being shown in Fig. 3 on each wing or aerofoil secured to the upper surface and extending rearwardly and of a shape offering a minimum of head resistance. Each lever 6 is connected by 25 links 7 to a spindle or bar 8 which is so guided that it can be reciprocated but cannot rotate. The end 9 of the bar 8 remote from the links is screw-threaded and passes through a nut 10 which is shaped on its exterior to form a pulley. The other end of the bar 8 is guided by a bearing 21. The pulley nut 10 is held between a pair of brackets 11 so that it can be rotated freely in either direction by means of a cable 12 30 passing over guide pulleys 25, to an operating wheel 26 controlled by a hand wheel 27, in a convenient position for the pilot. The brackets 11 also form bearings for the bar 8. Rotation of the hand-wheel 27 and therefore of the pulley-nut 10 results in reciprocation 35 of each screw-threaded bar 8, 9, and consequently of movement of the nose 2 about its hinges 13. The pulley-nuts 10 for the bars 8, 9, and levers 6 on both wings, are 40 worked by the same control, the cable 12 passing from one wing around the wheel 26 over the pulleys 25 to the other wing. Only one wing is shown in Fig. 3, but the cable 12 and guide pulleys 25 are indicated, the 45 apparatus on the other wing being identical to that shown.

Each screw-threaded bar 8, 9, also carries a short stub shaft 14 for another pulley 15 over which a cable 16 passes and is connected to an arm or lever 17 fixed to the lower or upper surface of the rear flap 3 similarly to that adopted with ordinary ailerons. The end of the stub shaft 14 passes through a slot 43 in a plate 25' so as to prevent the bar 8 from turning. The cables 16 50 take the place of the usual aileron cable and may be similarly controlled, there being a suitable number of levers 17 and cables 16 for instance two on each wing as shown in Fig. 3. Consequently, while the rear flap 3

may be controlled independently as an aileron, it can be moved simultaneously with the nose owing to the reciprocation of the screw-threaded bars 8, 9, carrying the pulleys 15 over which the cables 16 pass. The 70 cables 16 from each wing are led over suitable guide pulleys 28 to a control lever 29 of usual form.

When the wings are arranged so that lateral stabilizing is effected by an increase of 75 camber on one side of the machine, and a decrease on the other, the pulley 15 may be dispensed with and the screwed end of the bar 8, 9, directly connected to the lever 17 by a member such as a tube 30 capable of 80 taking tension and compression as indicated in Fig. 4.

The mechanism may be set or arranged in the aerofoil and therefore offers no head resistance. The nose and rear flaps may be 85 divided instead of each extending along the whole length of an aerofoil, and the portions on one side may be arranged to positively operate those on the other side for stabilizing purposes. Such a modification is illustrated in Figs. 5 and 6 in which similar reference numerals indicate corresponding parts in the other figures. A cross-tie cable 20 on the upper aerofoil is led over guide pulleys 18 to levers 17 which are arranged on 90 the upper sides of the aileron or movable trailing portions 3 so that they operate in reverse angles of deflection. The ailerons of the upper and lower aerofoils are connected as usual by cables or cross-ties 19 so 95 that they work in unison. The cable 16 of the lower aerofoil is connected to the usual control lever. This arrangement enables the ailerons to be controlled independently of the nose 2, as in ordinary practice, or in 100 conjunction with the nose 2 for variation of camber. The central portion or portions of rear flaps 3 in Fig. 6 may be provided with camber mechanism of the kind above referred to and illustrated by Fig. 4, wherein 110 the pulley 15 is dispensed with and the screwed end of the bar 8, 9, is connected to the lever 17 by a tube or like member 30.

In the form shown in Figs. 7, 8, and 9, a single screw-threaded bar 9 is arranged near 115 the center of the aerofoil for operating all the levers 6, 17. The screw-threaded bar 9 is fitted with a nut in the form of a pulley 10 adapted to be rotated by a cable 31 by means of suitable control lever or hand 120 wheel near the pilot.

When the pulley 10 is rotated the screw-threaded bar 9 is reciprocated and oscillates a lever 32 pivoted at 33, and to which lever the bar 9 is pivotally connected at 34. The 12 cables 35, 36, connected to the lever 32, either cross over each other and pass around guide pulleys 42 and are attached to the levers 6 and 17, as shown at the left hand side of Fig. 9, or they pass direct from the 130

lever 32, and are connected to levers 37 pivoted at 38 and having arms 39 to which the levers 6 are connected by link rods 40, the levers 6 being linked to the levers 17 by 5 tubes or rods 30.

Fig. 9 shows two outer wings consisting of a fixed portion 1, a hinged nose 2 and hinged rear flap 3 and a central fixed plane 41.

I claim,

10 1. An aerofoil having an initial section designed for the purpose of giving a high lift/drift ratio and provided with a hinged nose and a hinged rear flap, forming separate rigid elements, controlling means for 15 moving said nose and flap upwardly and downwardly together, for the purpose of varying the angles of entry and trail simultaneously, and additional controlling means for further deflecting said rear flap upwardly and downwardly for the purpose of 20 lateral control, substantially as hereinbefore set forth.

2. An aerofoil having an initial section designed for the purpose of giving a high 25 lift/drift ratio, and provided with a hinged nose and a hinged rear flap, forming separate rigid elements, levers rigidly attached to said nose and rear flap, mechanism connected to said levers, adapted to move said 30 levers simultaneously, said mechanism in-

cluding a reciprocating bar, links connecting one end of said bar to one of said levers on said nose, a pulley on said bar, a cable passing around said pulley and connected to one of said levers on said rear flap, and 35 means for reciprocating said bar, substantially as and for the purpose hereinbefore set forth.

3. An aerofoil having an initial section 40 designed for the purpose of giving a high lift/drift ratio, and provided with a hinged nose and a hinged rear flap, means for lowering and raising said rear flap independently of the nose for stabilizing purposes, and means for lowering and raising said 45 nose, said nose lowering and raising means being adapted to operate said rear flap lowering and raising means, for the purpose of insuring simultaneous operation of the nose and rear flap, for the purpose of changing 50 the camber of the section, substantially as and for the purpose hereinbefore set forth.

In testimony whereof I have signed my name to this specification in the presence of two subscribing witnesses.

MAURICE FRANCIS HUXLEY.
